UNITED STATES PATENT OFFICE.

EDWARD A. WAGENER, OF OKLAHOMA, OKLAHOMA, ASSIGNOR OF ONE-HALF TO
CHARLES E. CLOSE, OF OKLAHOMA, OKLAHOMA.

WRENCH.

1,033,768.

Specification of Letters Patent. Patented July 23, 1912.

Application filed March 21, 1911. Serial No. 615,832.

To all whom it may concern:

Be it known that I, EDWARD A. WAGENER, a citizen of the United States, residing at Oklahoma city, in the county of Oklahoma and State of Oklahoma, have invented new and useful Improvements in Wrenches, of which the following is a specification.

This invention relates to actuating mechanism for wrenches or the like, and the object 10 of the invention is to provide simple and effective means whereby the sliding jaw of a wrench or similar structure may be easily and quickly operated to move the said jaw and which also has its parts so constructed and arranged as to rigidly and effectively sustain the sliding jaw on the shank of the wrench when the said jaw has been adjusted.

With the above and other objects in view which will appear as the nature of the description progresses, the invention resides in the novel construction and arrangement of parts hereinafter fully described and claimed.

In the drawings the figure represents a 25 side view of the wrench with parts in section.

In the accompanying drawings and referring to the figure thereof, the numeral 1 designates the shank of an ordinary wrench, 30 and 2 the head thereof. The upper face of the wrench is provided with teeth or serrations 3, the same being arranged preferably at an angle of 45°.

4 indicates the sliding jaw. This jaw is 35 formed with the usual legs or bails 5 which are adapted to envelop the shank 1. The upper portion of the jaw is formed with a recess or pocket 6 for the reception of the jaw actuating mechanism. Within the 40 pocket 6 is loosely mounted a shoe 7, the said shoe having its lower face provided with teeth 8, the same adapted to coact with the teeth 3 of the shank 1. The shoe 7 is formed adjacent one of its ends with a 45 curved opening 9, the said opening being approximately semi-cylindrical. The pocket 6 is of an approximately rectangular formation and arranged in communication with the upper and front walls provided by the 50 said pocket, the sliding jaw is formed with a second circular depression designated by the numeral 10.

The numeral 11 designates a link having a reduced body portion 40. This link has 55 its opposite ends provided with curved

heads 12 and 13. The head 13 is adapted to engage the semicircular opening of the shoe 7, while the curved head 12 is adapted to engage within the curved depression 10 and the body portion 40 adapted to engage an 60 inclined stop 30 arranged adjacent said depression. The heads 10 both snugly engage the depressions and the said link 11 is adapted to serve as a swivel for the shoe 7.

Positioned between and engaging the 65 upper wall of the pocket and the top of the shoe 7 is a substantially U-shaped spring 14, the said spring exerting pressure so as to force the teeth 8 of the shoe into engagement with the teeth 3 of the shank. The shoe 7 70 is formed with a rearwardly extending tail 15 and the movable jaw is provided with an opening or cut away portion 16 which communicates with the pocket 6. Pivoted between the walls provided by the said cut 75 away portions 16, and as indicated by the numeral 17, is a finger 18. This finger is adapted to extend within the pocket and to underlie the tail 15 of the shoe 7. The opposite end of the said finger is prefer- 80 ably formed with a head 19, the latter projecting a suitable distance beyond the rear face of the slideable jaw 4.

In operating the device, downward pressure is exerted upon the head 19 of the 85 finger 18, causing the same to rotate upon its pivot 17 and to force the teeth of the shoe 7 out of engagement with the teeth of the shank. This movement, it will be noted, causes each of the teeth 8 to raise 90 one after another, starting from the tooth adjacent the tail 15 and the link 11 acting as a swivel raises the last tooth and at the same time swings the shoe 7 rearwardly or toward the end of the pocket occupied by the finger 18.

Having thus fully described the invention, what I claim as new, is:—

In combination a toothed member, a 100 chambered casing mounted for movement with relation to the toothed member, one wall of the said casing being provided with a cylindrical recess opening at its side into the chamber, an inclined stop arranged adjacent the said open side of the recess, a 105 toothed shoe mounted in the chamber and provided with a cylindrical recess opening at its side into the chamber, a link having a reduced body portion and enlarged cylindri- 110 cal ends, said ends fitting in the recess, a

spring adapted to move and hold the shoe in engagement with the toothed member, the body portion of the link being adapted to engage said shoulder and thus limit the 5 movement of the shoe in one direction, and means by which the shoe may be moved out of engagement with the toothed member.

In testimony whereof I affix my signature in presence of two witnesses.

EDWARD A. WAGENER.

Witnesses:

E. G. WILSON,
C. E. CLOSE.
